J. C. STURGEON,
FIREARM BARREL COOLING MECHANISM.
APPLICATION FILED APR. 27, 1917.

1,290,853.

Patented Jan. 7, 1919.

Inventor.
John C. Sturgeon

UNITED STATES PATENT OFFICE.

JOHN C. STURGEON, OF ERIE, PENNSYLVANIA.

FIREARM-BARREL-COOLING MECHANISM.

1,290,853.

Specification of Letters Patent.

Patented Jan. 7, 1919.

Original application filed December 22, 1916, Serial No. 138,330. Divided and this application filed April 27, 1917. Serial No. 164,919.

To all whom it may concern:

Be it known that I, JOHN C. STURGEON, a citizen of the United States, residing at Erie, in the county of Erie and State of Pennsylvania, have invented certain new and useful Improvements in Firearm-Barrel-Cooling Mechanism; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

This application being a division of the application filed by me December 22, 1916, Serial No. 138,330.

The improvements which form the subject of this application relate to fire-arms, and particularly to mechanism for cooling the barrels thereof, and has for its object the more effective cooling of the barrels of fire-arms by the use of air, than is accomplished by the air-cooling mechanism now in use. In accomplishing this result I secure to the barrel longitudinal radiating strips of highly conductive metal preferably longitudinally corrugated, so as to present the maximum radiating surface to the action of air passing thereover, so secured to the barrel that effective conductive contact therewith is at all times maintained regardless of any changes of temperature of the barrel. These radiating strips extend from the periphery of the barrel outward, and are inclosed by a metal shell open at its rear end, and extending beyond the end of the barrel at its front end. I preferably secure the radiating strips to the barrel by making longitudinal grooves in the periphery of the barrel and firmly securing the inner edges of the longitudinal radiating strips therein, so that no differences either of the temperature or expansion of the metals comprising the barrel and the radiating strips can, in any way, affect the conductive contact between them.

A further object of my invention is to provide longitudinal arms secured to the muzzle end of the barrel to which conical deflecting disks are secured within the shell

covering the radiators, whereby a considerable portion of the gases of discharge passing from the muzzle of the barrel are deflected outward so as to produce a strong draft of air through the shell from the open rear end thereof over the radiators inclosed thereby. These and other features of this invention are hereinafter fully set forth and described and illustrated in the accompanying drawings in which:—

Figure 1, shows a longitudinal section partially in elevation, of a gun barrel embodying my invention.

Fig. 2, shows an enlarged view of a transverse section of the same on the line *a* in Fig. 1.

Fig. 3, shows an enlarged view of a transverse section of a modification of my invention.

Fig. 4, shows an enlarged front end view in elevation, of my invention.

In these drawings 1 indicates a gun-barrel provided at its rear end with an interrupted screw thread 2 by means of which it can be secured to a gun-frame (not shown), 3 a metal shell open at its rear end and extending some distance beyond the muzzle end of the barrel 1.

In the periphery of the barrel 1 as shown in Figs. 1 and 2, I make longitudinal dovetailed grooves 4 adapted to receive the properly formed inner edges 5 of thin sheet metal radiators 6 of superior heat conducting properties, such as copper or aluminum. These radiators 6 are preferably provided with longitudinal corrugations 7 substantially as shown in Figs. 1 and 2, whereby they present the maximum of radiating surface to the air passing over them.

In Fig. 3 I show a modified construction in which I make radial grooves 8 in the periphery of the barrel 1 of such width that the inner edges 9 of longitudinal strips 10, of thin radiating metal, such as copper or aluminum, can be inserted as illustrated in Fig. 3, and as copper and aluminum expand under heat approximately one-half times more than steel, any increase of temperature which will expand the barrel, will also expand the edges 9 of the radiating strips 10 inserted in the slots 8, so that they will be firmly pinched and

clamped by the slots 8, forming a complete conductive contact therewith, so as to effectively conduct heat from the barrel.

Between the barrel 1 and the inside of 5 the shell 3 I preferably provide the radiating strips 10 with corrugations 11, as illustrated in Fig. 3.

On the muzzle end of the barrel 1 I preferably secure a collar 12 provided with 10 arms 13 extending longitudinally outward in line with the bore 14 of the barrel, and to these arms I secure preferably a plurality of conical disks 15 within the end portion 16 of the shell 3 so that a considerable 15 portion of the gases from the discharge of the gun will be deflected outwardly by said disks, producing a strong suction through the shell 3 and thereby drawing a strong current of air over the radiators secured to 20 the barrel, and withdrawing the heat therefrom. The effectiveness of the conductive contacts between the barrel and the radiators, the increased available radiating surface presented by the corrugations therein, 25 as well as the action of the conical disks 15 at the end of the barrel, and the operation of the several parts of the device in correlation to each other, as hereinbefore described, it is believed render further description 30 thereof unnecessary.

Therefore having shown and described my invention so as to enable others skilled in the art to utilize the same, what I claim as new and desire to secure by Letters Patent, is—

1. In a gun, a barrel having longitudinal grooves in its periphery, longitudinal radiators of thin conductive metal having their inner edges secured in said grooves

so as to maintain conductive connection between the barrel and radiators under all changes of the temperature thereof. 40

2. In a gun, a barrel having longitudinal grooves in the periphery thereof, longitudinally corrugated radiators of higher conductive metal than that of the barrel having their inner edges so inserted in and secured in said grooves as to maintain a maximum conductive connection between the barrel and radiators under all variations of 45 50 the temperature thereof.

3. In a gun, a barrel, arms secured to the muzzle end thereof parallel with the axis of the bore of the barrel, conical disks secured to said arms, and a shell open at both ends 55 surrounding, but out of contact with the peripheries of said disks.

4. In a gun, a barrel, longitudinal radiators secured to the periphery thereof, arms secured to the muzzle end of the barrel parallel with the axis of the bore of the barrel, 60 conical disks secured to said arms, and a shell open at both ends inclosing the barrel, radiators and disks.

5. In a gun, a barrel having longitudinal 65 grooves in the periphery thereof, longitudinal radiators of thin conductive metal having their inner edges secured in said grooves so as to maintain conductive connection between the barrel and the radiators under 70 all variations of temperature, arms secured to the muzzle end of the barrel parallel with the bore thereof, conical disks secured to said arms, and a shell inclosing the barrel, radiators and disks. 75

In testimony whereof I affix my signature.

JOHN C. STURGEON.
